DESIGN FOR A PAPER NAPKIN HOLDER

Paul Tresenberg, Springfield Gardens, N. Y.

Application March 5, 1940, Serial No. 90,683

Term of patent 7 years

To all whom it may concern:

Be it known that I, Paul Tresenberg, a citizen of the United States, residing at Springfield Gardens, Long Island, in the county of Queens and State of New York, have invented a new, original, and ornamental Design for a Paper Napkin Holder, of which the following is a specification, reference being had to the accompanying drawing, forming part thereof.

In the drawing:

Fig. 1 is a front elevational view of a paper napkin holder, showing my new design, it being understood that the rear of the article is identical with the front thereof;

Fig. 2 is a side elevational view; and

Fig. 3 is a top plan view thereof.

I claim:

The ornamental design for a paper napkin holder, as shown and described.

PAUL TRESENBURG.
